UNITED STATES PATENT OFFICE.

MILTON L. DONAWAY, OF SOUTH BELLINGHAM, WASHINGTON.

WHEEL.

1,113,963.

Specification of Letters Patent.

Patented Oct. 20, 1914.

Application filed April 15, 1914. Serial No. 832,621.

To all whom it may concern:

Be it known that I, MILTON L. DONAWAY, a citizen of the United States, residing at South Bellingham, in the county of Whatcom and State of Washington, have invented certain new and useful Improvements in Wheels, of which the following is a specification, reference being had to the accompanying drawings.

10 This invention relates to improvements in wheels, and more particularly to cushioned wheels which are adapted for use upon vehicles.

15 An object of this invention is the provision of a wheel of this character which is provided with concentric rims between which cushioning blocks are mounted, the rims being readily detachable from each other and from the spokes of the wheel.

20 Another object of this invention is the provision of a wheel which is provided with concentric rims, the rims being maintained in their concentric relation by a plurality of adjustable spacing members, the outer 25 rim being connected to the hub by a plurality of adjustable spokes, the outer ends of which bear against the inner rim between adjacent spacing members of the rims.

With these and other objects in view, my 30 invention consists in the novel construction, combination, and arrangement of parts to be hereinafter more fully described, claimed, and illustrated in the accompanying drawing, in which,

35 Figure 1 is a side elevation of a portion of my improved wheel; Fig. 2 is a sectional view on the line 2—2 of Fig. 1; Fig. 3 is a sectional view on the line 3—3 of Fig. 1; and Fig. 4 is an elevational view partly in 40 section, of a slightly modified form of spoke.

Referring more particularly to the drawing, the numeral 1 designates the hub of my improved wheel, in which are mounted the inner ends of the inner sections 2 of the 45 adjustable spokes, the outer ends of the sections 2 of the spokes being interiorly threaded as at 3, for the reception of the threaded stems 4 of the outer sections 5 of the spokes. The outer section 5 of each spoke comprises 50 a head from which the threaded stem 4 projects inwardly, the head of each section having a forwardly extending semi-annular projection 6 which is swivelly mounted in the arcuate recess 7 of the clamping plate 8. 55 Each of the clamping plates 8 is provided on its opposite side edges with oppositely

extending flanges 9, for engagement with the opposite sides of the inner rim 10 of the wheel. An outer concentric rim 11 is also provided, the rims 10 and 11 being maintained in their concentric relation by means of the adjustable sectional spacing members 12. Each of the spacing members comprises an inner clamping plate 13 which is adapted to engage the outer face of the inner rim 10 and an outer clamping plate 14 which is adapted for engagement against the inner face of the outer rim 11. The inner clamping plate 13 is provided on its opposite end edges with inwardly extending flanges 15 which are adapted for engagement with the opposite sides of the rim 10, and the clamping plate 14 is provided on its opposite end edges with outwardly extending flanges 16 which are relatively longer than the flanges 15 of the plates 13 and are adapted to engage the opposite sides of the rim 11, which project slightly beyond the outer face thereof.

The inner plates 13 are provided with outwardly projecting reduced tubular extensions 17, the extensions being interiorly threaded for the reception of the adjusting bolts 18. The heads 19 of the adjusting bolts are provided with semi-annular projections 20 which are adapted for engagement in the arcuate recesses 21 formed in the inner faces of the plates 14. From this construction, it will be seen that the bolts 18 may be readily turned to force the plates 13 and 14 apart and into clamping engagement with the inner rim 10 and the outer rim 11, respectively, to maintain the rims in their concentric relation.

Formed at intervals around the circumference of the inner rim 10 on its outer face are pairs of spaced stop lugs or cleats 22, and similar lugs 23 are formed on the inner face of the outer rim 11 in radial alignment with the cleats 22, the clamping plates 13 which engage the inner rim of the wheel and the clamping plates 14 which engage the outer rim of the wheel being disposed between the pairs of cleats 22 and 23 respectively. The pairs of cleats 22 and 23 are spaced slightly from the opposite side edges of the clamping plates 13 and 14, respectively, and disposed between each clamping plate 13 and the inner rim 10 is a cushioning plate 24 which is composed of rubber or other suitable flexible material, the opposite ends of the plates 24 projecting

beyond the opposite side edges of the plates 13 for engagement with the stop lugs 22 on the rim 10. Similar cushioning plates 25 are disposed between the plates 14 and the rim 11 for engagement at their opposite ends with the lugs 23 on the inner face of the outer rim; and with this construction, slight circumferential movement of the outer rim 11 with relation to the inner rim 10 is allowed, by reason of the flexibility of the projecting portions of the cushioning plates 24 and 25. A cushioning tire 26 of composition rubber or other flexible material, is mounted upon the outer face of the outer rim 11, the tire being held in its relative position with relation to the rim, by means of the extremities of the flanges 16 of the clamping plates 14, which engage the opposite sides of the tire. The rims 10 and 11 are preferably composed of thin steel which has a certain amount of inherent resiliency.

In assembling my improved wheel, the outer sections 5 of the spokes are rotated to move the same inwardly within the outer ends of the inner sections of the spokes, and the rims 10 and 11 are connected together in proper concentric relation to each other by the spacing members 12 whereupon the rims are placed in their concentric relation 30 with the hub 1 of the wheel so that the outer sections 5 of the spokes may be turned in the reverse direction to move the clamping plates 8 outwardly into engagement with the inner rim 10. When the sections of the 35 wheel are assembled in this manner, the wheel is ready for use, and owing to the flexibility of the rims, the shocks which are ordinarily imposed upon the body of the vehicle are absorbed equally by the rims. It will be seen that a slight circumferential 40 movement of the inner rim relative to the outer rim is allowed, owing to the projecting ends of the cushioning plates 24 and 25 which engage with the stop lugs 22 and 23 45 of the inner rim and the outer rim, respectively.

In Fig. 4 of the drawing, I have illustrated an alternative form of the inner section of the spoke which is adapted for use

in connection with my improved wheel, the 50 inner section 27 of the spoke in this form of device being constructed of wood in the usual manner, and having a tubular metallic sleeve 28 mounted on the outer end thereof, the bore of the sleeve being enlarged as at 55 29 for the reception of the outer end of the spoke, and the forward end of the bore being threaded as at 30 to receive the threaded stem 4 of the outer section of the spoke which is clearly illustrated in Fig. 3. 60

Having thus fully described my invention, what I desire to secure and claim by Letters Patent is:—

1. A vehicle wheel comprising a hub, spokes extending radially from the hub, an inner rim carried upon the outer ends of the spokes, an outer concentric rim, spacing members disposed between said outer and inner rims, said spacing members comprising adjustably connected clamping plates 70 for engagement against the opposing faces of said rims, cushioning blocks disposed between said clamping plates and said rims, and means for resiliently holding said spacing members in adjusted position with relation to the rims.

2. A vehicle wheel comprising a hub, spokes extending radially from said hub, an inner rim carried upon the outer ends of said spokes, an outer concentric rim, pairs 80 of spaced lugs formed at intervals upon the inner face of the outer rim, spacing members disposed between said inner and outer rims, said spacing members including plates for engagement between the pairs of lugs on 85 the inner face of said outer rim, and a cushioning block disposed between each plate and the inner face of the outer rim, the opposite ends of said cushioning blocks being adapted to project beyond the opposite sides 90 of said plates for engagement with the adjacent lugs, as and for the purpose described.

In testimony whereof I hereunto affix my signature in the presence of two witnesses.

MILTON L. DONAWAY.
